UNITED STATES PATENT OFFICE.

SARA BAXTER, OF NEW YORK, N. Y.

DESIGN FOR A CLASP.

SPECIFICATION forming part of Design No. 21,845, dated September 6, 1892.

Application filed August 10, 1892. Serial No. 442,718. Term of patent 3½ years.

To all whom it may concern:

Be it known that I, SARA BAXTER, a citizen of the United States, residing at New York city, in the county and State of New York, 5 have invented and produced a new and original Design for a Clasp, of which the following is a specification.

My invention relates to an ornamental design for a garment-clasp.

10 The figure is a front elevation of a clasp, showing my design.

The leading features of my design are the oppositely - arranged body portions of the clasp, one simulating an eagle and the other 15 a Maltese cross. One body portion of the design simulates a spread-eagle and the oppo-

site body portion represents a Maltese cross, on the center of which is produced a five-pointed star. Above the cross is a loop-like figure, from which extend the clasp-chains, 20 which fall in a graceful curve and are held in the bill of the eagle, the ends of the chains falling, apparently, from one side of the eagle's mouth.

I claim—

25 The design for a clasp herein shown and described.

SARA BAXTER.
